(57) CLAIM

We claim the ornamental design for a combined sprinkler head grass trimmer and cleaner, as shown and described.

DESCRIPTION

FIG. 1 is a perspective view of a combined sprinkler head grass trimmer and cleaner showing our new design;

FIG. 2 is a side elevational view thereof;

FIG. 3 is a front elevational view thereof;

FIG. 4 is an elevational view of the opposing side thereof;

FIG. 5 is a rear elevational view thereof;

FIG. 6 is a top plan view thereof; and,

FIG. 7 is a bottom plan view thereof.

The drawings of FIGS. 1–5 are illustrated as broken away to show indeterminate length
